2,487,451

PROPORTIONAL DIVIDER

John Kurmer, Philadelphia, Pa.

Application July 27, 1948, Serial No. 40,869

3 Claims. (Cl. 33—150)

1

This invention relates to proportional dividers and is particularly concerned with the provision of an instrument of this kind in which it is possible to set the points at one end of the instrument to a desired interval and then to lock and hold them in fixed relationship while setting the points at the opposite end to some other interval by adjusting the position of the pivot upon which the two legs of the dividers are adapted to swing. After this has been done it is also an object of my invention to provide means whereby the leg pivot may be locked in the position which it assumed in establishing the interval between said second pair of points so that said first lock may be released and the instrument used as a proportional dividers. At the same time it is an object of the invention to provide an instrument of the character described which is simple, rugged, accurate, easily manipulated and relatively inexpensive to manufacture.

How the foregoing objects are attained is illustrated in preferred form in the accompanying drawings wherein:

Figure 1 is a plan view of my improved instrument with the divider legs in partly opened position;

Figure 2 is a section on an enlarged scale taken as indicated by the line 2—2 on Figure 1;

Figure 3 is a section, also on an enlarged scale, taken as indicated by the line 3—3 on Figure 1;

Figure 4 is a section on line 4—4 of Figure 2;

Figure 5 is a top end view of Figure 1;

Figure 6 is a side view of Figure 1;

Figure 7 is an end view showing how the points of the dividers legs are bent in so that they coincide when the legs of the instrument are in closed position; and

Figure 8 is a section taken as indicated by the line 8—8 of Figure 2 but with the legs of the instrument in closed position in order to better illustrate certain of the features of my invention.

The divider legs 9 and 10 of my improved instrument are provided with divider pins 11, 12, 13 and 14 which are arranged at right angles to the plane in which the legs swing around the pivot shaft 15. The bodies of these pins are held in their perpendicular relationship to the legs by means of bushings 11a, 12a, 13a and 14a and are adjustable as to depth and held in place by the set screws 11b, 12b, 13b and 14b.

At their lower ends the pins are bent inward so that their tips or points will lie along the center line of the legs 9 and 10 and further so that the two tips at each end of the divider may coin-

cide when the legs are in closed position as shown in Figure 7.

A third, or what I term a "reference" leg 16, is inserted between the divider legs 9 and 10, one end of which reference leg is provided with a slotted guideway 17 along one side of which is a rack 18. The guideway is milled out or machined above and below to provide a central shouldered portion 19 at each side of the slot. The opposite end of the reference leg is reduced in thickness in order to provide room for the accommodation of the locking arms 20 and 21 which will be described more fully later on in connection with the locking assembly.

The ends of the divider legs in which the pivot shaft is located are also provided with slotted guideways 22 and 23, the inner faces of the legs being machined or milled out to provide the shouldered portions 24 and 25.

The pivot shaft 15 is part of what I term a pivot assembly, and this assembly includes in addition an upper slide 26, a lower slide 27, an upper intermediate slide 28 and a lower intermediate slide 29, the slides 26 and 27 having central projections 26a and 27a which fit into the slots 22 and 23, and the slides 28 and 29 being adapted to move along the shouldered portions 24 and 25 respectively. There are also included in the assembly an upper slide 30 and a lower slide 31 which are adapted to move along the central shoulder or shelf 19 of the reference leg 16. Between the slides 28 and 30, and between the slides 29 and 31 are suitable spacer washers 32 and 33, these washers being of a thickness which will insure the existence of a snug but sliding fit between the contiguous faces of the legs 9, 10 and 16. This prevents cocking of the legs with respect to one another and assures movement thereof in truly parallel planes.

Centrally the shaft 15 is formed with an integral pinion 34 which is adapted to mesh with the teeth on the rack 18, and on its upper squared portion 15a is fitted a thumb wheel 35 by means of which the shaft may be rotated. A collar or nut 36 at the top and another 37 at the bottom of the shaft 15 serve to hold the assembly together, these nuts or collars preferably being pinned to the shaft by the pins 36a and 37a, or otherwise suitably fixed to the shaft. It should be noted that the thickness or depth of the pinion 34 should be exactly the same as the thickness of the shoulders 19 on which the slides 30 and 31 are adapted to rest. In this way, when the pivot assembly is locked into position, as will be described below, the reference leg becomes fixed

with relation to the pinion because the shoulders and the pinion will be gripped by the slides.

At the underside of the instrument I provide the locking or clamping plate 38 having an enlarged central aperture 39 which fits around the lower end of the shaft 15. This plate is roughly coextensive in length with the length of the adjacent slide 27 as shown to best advantage in Figure 8, and at one end of the plate 38 is a set screw 40 the point of which is adapted to project into a hollow 41 in the adjacent face of the slide 27. At the other end the plate carries a thumb screw 42 the point of which is adapted to fit into a hollow 43 in the adjacent face of the other end of the slide 27. It will be obvious that by means of this clamping plate with its set screw 40 and thumb screw 42, it is possible to clamp together all of the parts which are mounted upon the pivot shaft 15.

To go back to the locking assembly, which includes the arms 20 and 21, it should be pointed out first that these arms are of equal length and that their inner ends are coupled together at the center upon a pivot in the form of a thumb screw 44, the end of each being provided with an enlarged hub portion 45 for this purpose. These hub portions have central sleeve portions 46 around which is located a slide 47 adapted to move along the slotted longitudinal guideway 48, which latter constitutes a second guideway in the leg 16 formed in the end opposite to the guideway 17 and the rack 18. The screw has a shoulder 44a which abuts against the upper hub 45 and the central reduced portion 44b is free to rotate in the upper hub 45 but is threaded into the lower hub 45 as shown to best advantage in Figure 3. It will be seen, therefore, that when the screw is turned down the two hubs 45 are drawn together in order to clamp them tightly against the opposing faces of the leg 16. The opposite end of the arm 20 is pivoted at the adjacent outer end of the leg 9 upon a pin 20a the axis of which coincides with the point of the corresponding divider pin. Similarly, the outer end of the arm 21 is pivoted upon a pin 21a the axis of which coincides with the point of the corresponding divider pin 12 on the adjacent end of the divider leg 10.

The inner corners of each end of both of the divider legs are slotted as at 49, which slots are adapted to embrace the adjacent divider pins so that the instrument may be fully closed and the points of the pins brought together as shown in Figure 7. Also, the upper arm 9 is slotted as at 50 to accommodate the shank of the thumb screw 44 and the inner face of the leg 10 is recessed as at 51 to accommodate the hub 45 of the arm 21. The inner faces of the lower ends of the divider legs 9 and 10 are each equipped with a stop lug or pin 52, the axis of which is located on the center line of the leg and against which the lower end of the reference leg 16 is adapted to abut. The legs may be provided with whatever scales are desired, in the present instance the upper leg being shown as having a scale 53 which cooperates with an index point 54 on the upper slide 26.

The procedure to be followed in using the instrument will now be described.

1. With the screws 42 and 44 retracted or in their loosened position, close the legs completely.

2. Now, shift the reference leg 16 until its lower end touches the stop pins 52.

3. Tighten the thumb screw 44 and then move the pivot as close to a 1:1 ratio as possible by rotating the shaft 15 by means of the thumb wheel 35 which, of course, will turn the pinion

34 and cause the entire fulcrum assembly to slide along the guideways in the legs.

4. Now, tighten the thumb screw 42 in order to clamp the parts together around the shaft 15 and loosen the thumb screw 44.

5. The points of the divider pins 11 and 12 should now be set to span the larger of the two desired intervals, after which the thumb screw 44 should be tightened and the thumb screw 42 loosened.

6. The thumb wheel 35 is then turned in order to slide the pivot assembly to the position it must occupy where the points of the pins 13 and 14 span the second and smaller of the two desired intervals.

7. When this has been accomplished, tighten the thumb screw 42 and loosen the thumb screw 44 and proceed to use the instrument as a proportional dividers.

20 It will be seen that the leg 16, which I term a "reference" leg, is in reality a "floating" member in my instrument. It is made shorter than the divider legs 9 and 10 so that when the divider is closed and all the legs coincide, the leg 16 can be shifted slightly from one end to the other until stopped either by the pins 20a and 21a at the top or by the stop pins 52 at the bottom. This floating feature compensates for the shifting of legs 9 and 10 with respect to leg 16 which occurs when the position of the pivot assembly is changed while the locking arms 20 and 21 are rigidly fixed. If the leg 16 were not shorter than the legs 9 and 10, and a change in the pivot position were made under the conditions described above, then it would not be possible to close the dividers due to the shifting mentioned.

25 It will be understood, of course, that the operator initially positions the leg 16 as favorably as possible considering the ratio to be employed. 40 For example, if while the divider is closed, the pivot assembly initially is in approximately the 1:1 position, then the leg 16 should be placed against the stop pins 52, but should the fulcrum initially be in the 10:1 position, then the leg 16 is moved against the pins 20a and 21a.

30 In using the instrument, the end of the dividers which can be locked by the arms 20 and 21 and the thumb screw 44 is always set first and to the larger of the two desired intervals, after which 35 the other end of the dividers is set to the smaller interval in the manner described.

35 It will be seen that if the proper lock-unlock sequence is used with the thumb screw 42 and 44 then the locking arms 20 and 21, since they are 50 of equal length, will insure that the legs 9 and 10 form equal angles with the leg 16 which in turn assures the formation of two similar triangles, namely, one triangle whose apices are at the pivot center, the pin 20a center and the pin 21a center, and a second triangle whose apices are at the pivot center and at the centers of the pins 52. Hence 55 proportionality exists between the bases of these two triangles.

I claim:

1. Proportional dividers comprising a pair of divider legs, a pivot assembly connecting said legs and adjustable longitudinally thereof, divider pins arranged at right angles to the plane in which the legs swing around the pivot, a reference leg having a longitudinal guideway along which said pivot assembly is adapted to travel, a locking assembly consisting of a pair of arms of equal length pivoted together at one end with the opposite end of one arm pivoted to the end of one of the divider legs on an axis coinciding with

the point of the corresponding divider pin and with the opposite end of the other arm similarly pivoted to the cooperating end of the other divider leg, said reference leg being provided with a second longitudinal guideway along which the pivot of the locking assembly is adapted to travel, clamping means for holding the pivot assembly in a selected position, and clamping means for locking the pivot of the locking assembly in a fixed position with relation to said second guideway in the reference leg.

2. The dividers of claim 1 in which the pivot assembly for the divider legs includes a rotatable pivot shaft having a pinion and in which said first guide in the reference leg is provided with a rack arranged to mesh with said pinion.

3. Proportional dividers comprising a pair of divider legs, a pivot assembly, guideways on the legs, said pivot assembly including slides adapted to move along said guideways, divider pins arranged at right angles to the plane in which the legs swing around the pivot, a reference leg having a longitudinal guideway at one end with a rack therealong, said pivot assembly also including slides adapted to move along said guideway in 25

the reference leg, a locking assembly consisting of a pair of arms of equal length pivoted together at one end with the opposite end of one arm pivoted to the end of one of the divider legs on an axis coinciding with the point of the corresponding divider pin and with the opposite end of the other arm similarly pivoted to the cooperating end of the other divider leg, said reference leg being provided at its other end with a second longitudinal guideway, a slide associated with the pivot of the locking assembly and adapted to move along said second guideway, a rotatable pivot shaft associated with the pivot assembly for the divider legs including a pinion meshing with said rack, a thumb wheel for rotating said pivot shaft and its pinion, means for clamping the pivot assembly slides against the sides of the several legs, and clamping means for locking the arms and the pivot of the locking assembly in a fixed position with relation to said second guideway in the reference leg.

JOHN KURMER.
